(57) **CLAIM**

The ornamental design for a dental flosser, as shown and described.

DESCRIPTION

FIG. 1 is a front perspective view of an embodiment of a dental flosser showing our new design.

FIG. 2 is a rear perspective view of the dental flosser as shown in FIG. 1.

FIG. 3 is a close-up front perspective view of a portion of the dental flosser as shown in FIG. 1.

FIG. 4 is a front end elevation view of the dental flosser as shown in FIG. 1.

FIG. 5 is a rear end elevation view of the dental flosser as shown in FIG. 1.

FIG. 6 is a front elevation view of the dental flosser as shown in FIG. 1.

FIG. 7 is a rear elevation view of the dental flosser as shown in FIG. 1.

FIG. 8 is a bottom plan view of the dental flosser as shown in FIG. 1.

FIG. 9 is a top plan view of the dental flosser as shown in FIG. 1.

FIG. 10 is a front perspective view of another embodiment of a dental flosser showing our new design.

FIG. 11 is a rear perspective view of the dental flosser as shown in FIG. 10.

FIG. 12 is a close-up front perspective view of a portion of the dental flosser as shown in FIG. 1.

FIG. 13 is a front end elevation view of the dental flosser as shown in FIG. 10.

FIG. 14 is a rear end elevation view of the dental flosser as shown in FIG. 10.

FIG. 15 is a front elevation view of the dental flosser as shown in FIG. 10.

FIG. 16 is a rear elevation view of the dental flosser as shown in FIG. 10.

FIG. 17 is a bottom plan view of the dental flosser as shown in FIG. 10.

(Continued)

FIG. 18 is a top plan view of the dental flosser as shown in FIG. 10.

FIG. 19 is a front perspective view of a third embodiment of a dental flosser showing our new design.

FIG. 20 is a rear perspective view of the dental flosser as shown in FIG. 19.

FIG. 21 is a close-up front perspective view of a portion of the dental flosser as shown in FIG. 19.

FIG. 22 is a front end elevation view of the dental flosser as shown in FIG. 19.

FIG. 23 is a rear end elevation view of the dental flosser as shown in FIG. 19.

FIG. 24 is a front elevation view of the dental flosser as shown in FIG. 19.

FIG. 25 is a rear elevation view of the dental flosser as shown in FIG. 19.

FIG. 26 is a bottom plan view of the dental flosser as shown in FIG. 19; and,

FIG. 27 is a top plan view of the dental flosser as shown in FIG. 19.
